United States Patent Office

Des. 203,624
Patented Feb. 1, 1966

203,624

SAWBUCK

Claire K. Smith, 308 Richmond Road, Douglaston, N.Y.

Filed Nov. 30, 1964, Ser. No. 82,839

Term of patent 7 years

(Cl. D54—1)

FIG. 2

FIG. 1

FIG. 3

FIGURES 1 and 3 are front and side views, respectively, in elevation of a sawbuck constructed according to the invention; and

FIGURE 2 is a top view of the sawbuck shown in FIGURE 1.

I claim:

The ornamental design for a sawbuck, as shown.
